United States Patent Office

Des. 181,329
Patented Oct. 29, 1957

181,329

SPECTACLE FRONT

Harry Weissman, New Hyde Park, and Philip Pearlman,
New York, N. Y.

Application October 26, 1956, Serial No. 43,670

Term of patent 3½ years

(Cl. D57—1)

Fig. 1

Fig. 2

Fig. 1 is a top plan view of a spectacle front, showing our new design.

Fig. 2 is a front elevational view thereof.

Fig. 3 is a side elevational view thereof.

The dominant features of the design reside in the portions shown in full lines.

We claim:

The ornamental design for a spectacle front, substantially as shown and described.
